UNITED STATES PATENT OFFICE

2,398,337

INTERNAL-COMBUSTION ENGINE

Anthony L. Vissat, Wilkinsburg, Pa.

Application October 3, 1944, Serial No. 556,986

2 Claims.

(Cl. 74—50)

This invention relates to an improved internal combustion engine, and important objects and advantages thereof are to provide a more efficient internal combustion engine of the character described, which employs a straight shaft instead of the conventional crankshaft, which functions to impart rotation to its shaft through the straight-line reciprocations of the embodied piston rods with respect to the alignment of the latter with associated pistons, which maintains the full maximum compression of the fuel charges within the combustion chambers until ignition is effected, which is simple in its construction and arrangement, compact, durable, and comparatively economical in its manufacture, operation, fuel consumption, and maintenance, and which will operate with a minimum of vibration.

With the foregoing and other objects in view which will appear as the description proceeds, the invention resides in the novel construction, combination, and arrangement of parts herein specifically described and illustrated in the accompanying drawing, but it is to be understood that the latter is merely an embodiment of the invention, and that the actual needs of practice and manufacture may require certain mechanical variations from the embodiment shown. It is, therefore, not intended to limit the invention to the disclosure thereof herein illustrated, but rather to define such limitations in the scope of the claims hereunto appended.

In the drawing wherein like numerals of reference designate corresponding parts throughout the several views:

Figure 1 is a sectional elevation illustrating the invention as applied to an internal combustion engine.

Figure 2 is an elevational view thereof taken at right angles thereto. Figure 3 is a side view of the shaft with associated cams. Figures 4 and 5 are, respectively, side and end views of the upper cam block. Figure 6 is a side view of a guide plate, and Figure 7 is a similar view of the saddle.

Referring in detail to the drawing 1 represents a straight, crankless engine shaft, on which a plurality of spaced, circular cams 2 are eccentrically fixed in position by welding, or in any other suitable manner. The positions of the cams 2 of the shaft 1, relatively to each other, is such as to conform to the crank layout of a conventional type of crankshaft of a multi-cylinder internal combustion engine. The number of cylinders embodied in the latter, of course, determines the number of cams 2 carried by the straight shaft 1.

An impeller mechanism 3 is shiftably mounted

for vertical reciprocating movement on the shaft 1, and engages and encloses each of the cams 2. The impeller mechanism 3 comprises an upper cam block 4 and a lower cam block 5. The cam blocks 4 and 5 are respectively disposed above and below the associated cam 2, and are of uniform thickness with respect to the latter. The cam blocks 4 and 5 are secured in position by a pair of similar guide plates 6, which are secured in position by a plurality of bolts, respectively indicated at 7 and 8.

The guide plates 6 are disposed at respective sides of the cam 2, and the latter is accurately fitted but freely revoluble between the former. Each of the guide plates 6 is provided with an elongated vertically extending slot 9 for the passage of the shaft therethrough, and to allow the reciprocal vertical movement of the impeller mechanism 3 on said shaft 1.

20 A reinforcing saddle 10 overlaps the upper ends of the guide plates 6 and the interposed upper cam block 4, and is secured in position by the bolts 7. The lower end of each of the depending legs of the saddle 10 is formed with a recess 11 registering with the slots 9 in respective guide plates 6 to provide clearance from the shaft 1 during the vertical movement of the impeller mechanism 3 during the operation of the engine in the manner hereinafter to be described.

25 The assembled construction of the impeller mechanism 3 allows the latter to be removed from or replaced in the engine structure without disturbing the connection of the shaft 1. The slots 9 in the guide plates 6 have open upper ends, whereby said guide plates 6, assembled with the lower cam block 5, may be readily removed, when required for repairs and the like, from other parts of the impeller mechanism 3 and from the engine, by simply removing the upper securing bolts 7.

30 The inner edge of the upper cam block 4 is suitably formed to provide a curved cam face 12, which is disposed at the enlarged forward end portion of said upper cam block. The inner edge 45 of the lower cam block 5 is also formed to provide a suitable convexly curved cam face 13, which latter is likewise disposed in the forward end portion of said lower cam block. The terms "inner" and "forward" are herein respectively applied relatively to the axis of the shaft 1, and with respect to the rotation of the shaft with the cam 2 in the clockwise direction, as indicated by an arrow in Figure 1.

35 The forward enlarged end of the upper cam block 4 is formed with a vertically extending re-

cess 14 that is open at its lower end. An impact pawl 15 is pivotally suspended in said recess 14 by one of the upper securing bolts 1, which latter extends through the upper end thereof. The impact pawl 15 is engaged on its forward side by the lower free end of a flat spring 16. The upper end of the latter is fixed to the saddle by a bolt 17. The normal action of the spring 16 tends to force the impact pawl 15 rearwardly against the inner recess wall, whereby the free lower end of the impact pawl 15 will project through and beyond the surface of the cam face 12 of the upper cam block 4. The lower end of the impact pawl 15 is flat and functions to intermittently engage in a squared pocket seat 18, which latter is formed in the peripheral face of the cam 2.

The impeller mechanism 3 is supported by and secured to the lower end of the piston rod 19, which latter has its upper end attached to the piston 20 operating reciprocally in the engine cylinder 21. The attachment of the piston rod 19 with the piston 20 may be fixed, as shown, or may have a journaled connection therewith in the usual manner. The piston rod 19 and the piston 20 are preferably aligned with the axis of the engine shaft 1.

The vertical reciprocation of the impeller mechanism 3, actuated by the operation of the piston 20 in the cylinder 21, imparts rotations to the associated cam 2 and to the engine shaft 1 upon which said cam 2 is fixed. The pocket seat 18 in the cam 2 is disposed approximately in alignment with the axis of the shaft 1 and with the diametric center of the cam 2.

The position of the impact pawl 15, in the impeller mechanism 3, is such that the former will engage in the cam pocket seat 18 only when the cam 2 has shifted forwardly to a position approximately forty-five degrees from its vertical or dead center, as illustrated in Figure 1. During the rotation of the cam 2, the impact pawl 15 will be forced forwardly against the action of the spring 16 and the periphery of the cam 2 will slide idly by against said impact pawl. However, when the cam pocket seat 18 comes into registration with the impact pawl 15, the action of the spring 16 will instantly force the lower free end of said impact pawl into the cam pocket seat 18. In a four-cycle type of internal combustion engine, firing for the power stroke takes place every other time that the impact pawl so engages in the pocket seat 18.

Due to the relative curvatures of the periphery of the cam 2 and of the cam edge 12 of the upper cam block 4, the movement of the piston 20 is momentarily arrested at its maximum up-stroke while the cam 2 moves forwardly from its vertical dead center to its forty-five degree angular firing position, whereby maximum compression of the fuel charge within the compression chamber is maintained until the firing operation has been effected.

It will here be noted that in the operation of my improved crankless engine, the impeller mechanism 3 operates to impart rotation to the cam 2 and associated shaft 1 only during the power stroke of the piston 20 in the cylinder 21, and that the exhaust, suction, and compression strokes of the piston 20 are effected through the actuation of the impeller mechanism 3 by the rotating cam 2, in the manner not unlike the stroke operations of an engine embodying a conventional crankshaft.

Assuming that the invention is embodied in a four-cycle type, multi-cylinder internal combus-

tion engine, the operation is as follows: When the cam 2 is in its forward, angular firing position, with the impact pawl 15 engaged in the cam pocket seat 18, as shown in Figure 1, firing takes place to effect the power stroke of the piston 20, and the impeller mechanism 3 will be forced downwardly thereby. The engagement of the impact pawl 15 in the cam pocket seat 18 will obviously impart a momentary, definite, and a most powerfully effective impetus to the cam 2 tending to rotate the latter and the shaft 1. The driving action will be continued by the engagement of the cam face 12 of the upper cam block 4 against the periphery of the cam 2 until the latter reaches its most downward or full depending position at the end of the power stroke. It is, of course, evident that the angularity of the cam 2 when in the firing position may be varied to best meet conditions found in practice.

After the power stroke has been completed, the continuing rotation of the cam 2 will elevate the impeller mechanism 3 to thereby effect the exhaust stroke of the piston 20. Further rotation of the cam 2 will cause the latter to engage in the clearance cam face 13 in the lower cam block 5 and thereby shift the impeller mechanism 3 downwardly to effect the intake or suction stroke of the piston 20. During the suction stroke the impact pawl 15 will, of course, ineffectively snap into and out of the cam pocket seat 18.

Still further rotation of the cam 2 will again shift the impeller mechanism 3 upwardly to effect the compression stroke of the piston. As herein before stated, when the cam 2 is in its vertical dead center position like at the end of the compression stroke, the impeller mechanism 3 together with the attached piston 20, will be held at its maximum up-stroke, while the cam 2 is shifting forwardly from said vertical dead center to its angular firing position, whereby the fuel charge is maintained at full maximum compression until fired to effect the power stroke. This completes the four-cycle functions of the engine which are simply repeated in the continued operations of the engine in the usual manner.

With the foregoing detailed description taken in connection with the accompanying drawing, the construction and method of operation of the invention will be readily apparent to those skilled in the art to which the invention appertains, and while the present disclosure provides a practical embodiment of the invention, the latter is not confined to strict conformity therewith, but may embody changes and modifications that entail no material departure from the principle of the invention as specifically pointed out in the appended claims.

What I claim is:

1. A power mechanism comprising a straight shaft, a circular cam eccentrically fixed on said shaft and having a pocket seat formed in the peripheral face thereof, a cylinder provided with a reciprocally shiftable piston, a piston rod connected to said piston, an impeller mechanism secured to said rod and being mounted on said cam, said impeller mechanism including a pair of cam blocks having opposed cam faces in contact with the periphery of said cam for imparting reciprocal movement to said piston, and a spring controlled impact pawl pivotally connected with one of said blocks and engaging in said seat for imparting rotary impetus to said cam and to said shaft during the power stroke of said piston in said cylinder.
2. A power mechanism comprising a straight

shaft, a circular cam eccentrically fixed on said shaft and having a pocket seat formed in the peripheral face thereof, a cylinder provided with a reciprocally shiftable piston, a piston rod fixed to said piston, an impeller mechanism fixed to said rod and being mounted on said cam, said impeller mechanism including a pair of guide plates, said guide plates being disposed at respective sides of said cam and provided with elongated slots for the passage of the shaft, said impeller mechanism further including a pair of cam

blocks, said blocks being secured between said plates and having opposed cam faces in constant contact with the periphery of said cam for imparting reciprocal movement to said piston except during the power stroke of the latter, and a spring controlled impact pawl pivotally connected with one of said blocks and engaging in said seat for imparting rotary impetus to said cam and to said shaft during the power stroke of said piston in said cylinder.

ANTHONY L. VISSAT.
